W. A. WIESMAN

GUARD FOR PUNCH PRESSES

Filed July 16, 1924

FIG. 1.

INVENTOR.
WILLIAM A. WIESMAN.

Donald Red

ATTORNEY.

Patented Apr. 13, 1926.

UNITED STATES PATENT OFFICE.

WILLIAM A. WIESMAN, OF DAYTON, OHIO.

GUARD FOR PUNCH PRESSES.

Application filed July 16, 1924. Serial No. 726,331.

To all whom it may concern:

Be it known that I, WILLIAM A. WIESMAN, a citizen of the United States, residing at Dayton, in the county of Montgomery and State of Ohio, have invented certain new and useful Improvements in Guards for Punch Presses, of which the following is a specification, reference being had therein to the accompanying drawing.

10 This invention relates to guards for punch presses and similar machines and more particularly to that type of guard in which an oscillating arm is moved across the machine in front of the punch and die during 15 the downward movement of the punch and is restored to its initial position during the upward movement of the punch.

One object of the invention is to provide a guard of this kind which will operate 20 smoothly and uniformly.

25 A further object of the invention is to provide such a guard with means for absorbing the shock which is due to the stopping and reversing of the direction of movement of the guard.

Other objects of the invention will appear as the device is described in detail.

In the accompanying drawings Fig. 1 is 30 a front elevation showing my invention applied to a punch press; Fig. 2 is a section taken on the line 2—2 of Fig. 1; and Fig. 3 is a section taken on the line 3—3 of Fig. 1.

35 In these drawings I have illustrated my invention in connection with an oscillating guard of a well known construction and have shown the same as applied to an ordinary punch press. It will be apparent, however, that the invention may be utilized 40 in connection with guards of various kinds, which may be applied to machines of different kinds.

The punch press, as here shown, comprises 45 a main frame 1 having a die block 2 near the lower end thereof. Slidably mounted in the frame is a plunger 3 which carries the punch 4. This plunger is connected at its upper end with a bearing 5 which engages the offset portion of the crank shaft 6 which is journaled in bearings 7 at the 50 upper end of the frame, whereby the rotation of the crank shaft will impart vertical reciprocatory movement to the plunger. The guard may be mounted on the machine 55 in any suitable manner but, as here shown, a cross bar 8 is mounted in brackets 9 which are rigidly secured to the main frame on the respective sides of the plunger. This cross bar is provided with an upwardly extending portion or standard 10 having a 60 vertical slot 11. Mounted on the standard is a suitable supporting structure adapted to carry the movable guard member and, in the present form of the device, this supporting structure comprises clamping members or washers 12 and 13 engaging, respectively, the rear and front faces of the standard 10 and clamped against the same by means of a bolt 14 which extends through the clamping members and through the slot 70 in the standard. The faces of the standard and of the clamping members are preferably serrated to hold the supporting structure positively against movement on the standard. The bolt 14 extends beyond the front 75 clamping member 13 and has mounted thereon a bushing 15 which is provided with a circumferential flange 16 so arranged as to form between the same and the clamping member 13, a groove or bearing. When the bolt is tightened down on the nut 14 the bushing and the two clamping members are rigidly secured to the standard 10 and constitute a rigid supporting structure. Mounted on this supporting structure is 80 an oscillating structure which, as here shown, comprises a head 17 confined in the groove between the flange 16 and the clamping member 13 and journaled on the bushing 15. This head has a downwardly extending 85 integral arm 18 which carries at its lower end a transverse bar 19, the ends of which project beyond the respective sides of the arm 18 and are provided with apertured end portions, 20, to receive the two parts, 90 21 and 22, of a guard arm 23, the upper ends of said parts extending some distance above the transverse bar 19. Rigidly secured to the head 17 is a rod or arm 24, arranged substantially parallel with the 100 transverse bar 19 and provided at its ends with a clamping device 25 to receive the upper end of the part 21 of the guard arm and rigidly connect the same to the rod 24. A second clamping member 26 is secured to the head 17 on that side thereof opposite the rod 24 and is adapted to receive the upper end portion of the part 22 of the guard arm and secure the same to the head. The oscillating structure, of which 105 the guard arm forms a part, may be rocked about its axis in any suitable manner which 110

will cause the lower end portion of the guard arm to sweep across the machine in timed relation to the movements of the plunger. In the present device a bearing block 27 is slidably and rotatably mounted on the rod 24 and has in its upper portion, a transverse bearing to receive a rod 28 which is connected with the bearing 5 of the plunger so as to move therewith and thus impart movement to the oscillating structure.

Associated with the oscillating structure are yieldable devices so arranged that they will serve to cushion the movements of the oscillating structure as the guard arm approaches one end or the other of its movement, thus absorbing the shock due to the sudden stopping and reversing of the direction of movement of the guard arm. These yieldable devices may take various forms and may be mounted in various ways but in that form of the device here shown I have provided the forward clamping member or washer 14 with downwardly diverging arms 29, which are here shown as formed integral therewith. Each of these arms is provided at its lower end with a tubular member 30 which constitutes a socket adapted to receive a coiled spring 31. The oscillating structure is provided with a part forming a stop which is adapted to engage the springs in said sockets and compress the same as the guard arm approaches the limit of its movement in one direction or the other. In the present construction, tubular members 30 are provided in their front walls with slots 32 which form guide-ways for the stop which is shown in the form of a pin 33 mounted in the arm 18 of the oscillating structure. Preferably the two tubular members 30 are formed in a single casting and the intermediate portion of said casting is slotted, as shown at 34, to form a continuation of the guides 32 in the sockets. Consequently the pin is guided in the slot during all parts of its movement and, further, by connecting the two tubular members one to the other the two arms 29 are braced one against the other and greater strength is imparted to the structure. The tubular members or sockets 30 are open at their outer ends to permit the springs to be inserted in and removed from the same and pins 35 extend through the ends of the tubular members to retain the springs therein. If desired, the stop or pin 33 may be slidably mounted on the oscillating structure to permit the same to be withdrawn from the slot or guideway to release the oscillating structure from the tension of the spring and facilitate its removal from, or mounting on, the supporting structure. As here shown, the arm 18 is provided with a hollow boss 36 forming a socket in which the pin 33 is

slidably mounted and a spring 37 is arranged within the socket and acts on the pin to hold the same normally in its rear-most or operative position. A handle 38 is connected with the pin and arranged beyond the forward end of the socket to provide means for retracting the pin.

While I have shown and described one embodiment of my invention I wish it to be understood that I do not desire to be limited to the details thereof as various modifications may appear to a person skilled in the art.

Having now fully described my invention, what I claim as new and desire to secure by Letters Patent, is:

1. The combination with a machine comprising a frame and a plunger mounted on said frame, of a guard arm movably mounted on said frame, means for imparting oscillatory movement to said guard arm in accordance with the movements of said plunger, a part connected with said guard arm and forming a stop, and yieldable devices arranged on the opposite sides of said stop and in the path thereof.

2. The combination with a machine comprising a frame and a plunger mounted on said frame, of a guard arm movably mounted on said frame, means for imparting oscillatory movement to said guard arm in accordance with the movements of said plunger, a part connected with said guard arm and forming a stop, hollow supporting members rigidly mounted on the respective sides of said stop and having slots to receive said stop, and springs mounted in said supporting members in the path of said stop.

3. In a device of the character described, a supporting structure, an oscillating structure pivotally mounted on said supporting structure and comprising a guard arm, means for actuating said oscillating structure, a stop carried by said oscillating structure, diverging arms carried by said supporting structure, and yieldable devices carried by the respective arms and arranged on opposite sides of and in the path of said stop.

4. In a device of the character described, a supporting structure, an oscillating structure pivotally mounted on said supporting structure and comprising a guard arm, means for actuating said oscillating structure, a stop carried by said oscillating structure, diverging arms carried by said supporting structure, sockets carried by said arms, and springs mounted in the respective sockets and arranged on opposite sides of and in the path of said stop.

5. In a device of the character described, a supporting structure, an oscillating structure pivotally mounted on said supporting structure and comprising a guard arm, means for actuating said oscillating struc-

ture, a stop carried by said oscillating structure, diverging arms carried by said supporting structure, tubular members carried by the ends of the respective arms and 5 adapted to receive said stop, springs mounted in the respective tubular members, said tubular members having their outer ends open to permit said springs to be inserted in and removed from the same, and removable 10 means to retain said springs in said tubular members.

6. In a device of the character described, a supporting structure, an oscillating structure pivotally mounted on said supporting 15 structure and comprising a guard arm, means for actuating said oscillating structure, a stop carried by said oscillating structure, diverging arms carried by said supporting structure, tubular members carried 20 by the ends of the respective arms and adapted to receive said stop, said tubular members being rigidly connected one to the other, and springs mounted in the respective tubular members and arranged to be engaged by said stop.

7. In a device of the character described, a supporting structure, an oscillating structure pivotally mounted on said supporting structure and comprising a guard arm, 30 means for actuating said oscillating structure, a stop carried by said oscillating structure, diverging arms carried by said supporting structure, said arms having at their lower ends part forming sockets and having longitudinal slots to receive said stop, and springs mounted in said sockets in the 35 path of said stop.

8. In a device of the character described, a supporting structure, an oscillating structure pivotally mounted on said supporting 40

structure and comprising a guard arm, means for actuating said oscillating structure, a stop carried by said oscillating structure, diverging arms carried by said supporting structure, said arms having at their 45 lower ends parts forming sockets and having longitudinal slots to receive said stop, and springs mounted in said sockets in the path of said stop, said sockets being connected one to the other by an intermediate 50 portion having a slot forming a continuation of the slots formed in said sockets.

9. In a device of the character described, a supporting structure, an oscillating structure pivotally mounted on said supporting structure and comprising a guard arm, means for actuating said oscillating structure, sockets mounted in fixed positions and spaced one from the other, springs mounted 55 in said sockets, and a stop carried by said oscillating structure and arranged to enter the space between said sockets and to engage said springs.

10. In a device of the character described, a supporting structure, an oscillating structure pivotally mounted on said supporting structure and comprising a guard arm, means for actuating said oscillating structure, sockets mounted in fixed positions and spaced one from the other, springs mounted 70 in said sockets, a stop movably mounted on said oscillating structure for movement into and out of the space between said sockets, and a spring acting on said stop to hold the same normally in the space between said 75 sockets.

In testimony whereof, I affix my signature hereto.

WILLIAM A. WIESMAN.
